UNITED STATES PATENT OFFICE.

EDSON DOE, OF SOUTH NEWBURY, VERMONT.

JOINTED LINK FOR ENGINES.

SPECIFICATION forming part of Letters Patent No. 349,485, dated September 21, 1886.

Application filed February 4, 1886. Serial No. 190,874. (No model.)

To all whom it may concern:

Be it known that I, EDSON DOE, of South Newbury, in the county of Orange and State of Vermont, have invented a new and useful Improvement in Jointed Links for Engines, of which the following is a full, clear, and exact description.

Reference is to be had to the accompanying drawings, forming a part of this specification, in which similar letters of reference indicate corresponding parts in all the figures.

Figure 1 is a side elevation of my improvement, shown as applied to the crank-shafts of the piston-rod and valve stem of an engine. Fig. 2 is a plan view of a part of the same. Fig. 3 is an elevation of the jointed link, showing the reverse side. Fig. 4 is a sectional elevation of the upper part of the link and the annular part of the joint. Fig. 5 is a sectional elevation of the lower part of the link, and showing the circular part of the joint in edge view.

The object of this invention is to provide jointed links for engines constructed in such a manner as to give a perfect lead and cut-off on both forward and back motion, each eccentric working independently of the other, and one part of the link being thus prevented from affecting the movement of the other part.

The invention consists in the combination, with the crank-shaft of an engine, the eccentrics attached thereto and their eccentric-rods, and the crank-shaft connected with the valve stem, of the jointed link and its holding-bar, as will be hereinafter fully described.

A represents a steam-cylinder; B, the piston; C, the piston-rod, and D the crank-shaft of a steam-engine. E represents the steam-chest; F, the valve; G, the valve-stem, and H the crank-shaft that operates the said valve. All of these parts are constructed and operate in the ordinary manner. The valve-stem G is connected with the upper crank-arm, I, of the shaft H, and upon the crank-pin of the lower crank-arm, J, of the said shaft is placed a square bearing block, K, which slides in the slot of the link. The link is made in two parts, L M, which are curved in the manner of an ordinary solid link. The lower end of

the upper part, L, of the link is secured by 50 bolts or rivets to the upper part of the annular plate N, which forms a part of the link-joint. The annular plate N is made in two parts with flanges upon their ends to receive the bolts by means of which the said parts 55 are secured to each other. In the concave edge of the annular plate N is formed an annular groove, O, to receive the annular rib P, formed upon the edge of the circular plate Q, which forms the other part of the link-joint, and to which the upper end of the lower part, M, of the link is secured by bolts or rivets. Upon the outer parts of the concave edges of the parts L M of the link are formed lugs to which are pivoted the ends of the 60 bars R S. The other ends of the bars R S are connected by straps or other suitable means with the eccentrics T U, attached to the shaft D, with the crank V of which the piston-rod C is connected. To the center of 70 the circular plate Q is attached or upon it is formed a pin, W, to which is pivoted the end of a bar, X, the other end of which is connected with the shaft D by a strap or other suitable coupling, so as to hold the link always at the same distance from the said shaft D. To the center pin, W, is also pivoted the lower end of the short connecting-bar Y, the other end of which is pivoted to the end of an arm of the elbow-lever Z. To the other 80 arm of the elbow-lever Z is pivoted the end of a rod, a, which extends into such a position that it can be readily reached and operated by the engineer to reverse the motion or to cut off the steam at any desired 85 point of the stroke. With this construction the movements of the two parts of the link will be independent of each other, so that the forward movement of one part will not be affected by the back movement of the other 90 part, and the lead will be the same on both sides of the valve.

Having thus fully described my invention, I claim as new and desire to secure by Letters Patent—

1. An improved link for engines, consisting of an upper part provided with an annular grooved plate and a lower part provided

with an annular ribbed plate fitting in the said grooved plate, substantially as herein shown and described.

2. A link for engines, consisting of the upper part, L, provided with apertured plate N, having annular groove O, and the lower part, M, provided with the plate Q, having annular

rib P and pin W, substantially as herein shown and described.

EDSON DOE.
